DESIGN FOR SLACKS

Ben S. Graber, New York, N. Y.

Application November 2, 1942, Serial No. 108,676

Term of patent 3½ years

To all whom it may concern:

Be it known that I, Ben S. Graber, a citizen of the United States of America, residing in New York city, county of New York, and State of New York, have invented a new, original, and ornamental Design for Slacks, of which the following is a specification, reference being had to the accompanying drawing, forming part thereof.

Fig. 1 is a front view of a pair of slacks showing my new design,

Fig. 2 is a rear view thereof,
Fig. 3 is a fragmentary view of the slacks shown in Fig. 1 in partially opened position, and

Fig. 4 is a fragmentary view of the slacks shown in Figure 1 in fully opened position.

I claim:

The ornamental design for slacks, substantially as shown.

BEN S. GRABER.
